UNITED STATES PATENT OFFICE

123,399

DESIGN FOR A COMBINED WORK BENCH AND CABINET OR SIMILAR ARTICLE

Alexander P. Fox, University City, and August Daniel Reisert, St. Louis, Mo., assignors to Lincoln Engineering Company, St. Louis, Mo., a corporation of Missouri

Application August 23, 1940, Serial No. 94,577

Term of patent 7 years

To all whom it may concern:

Be it known that we, Alexander P. Fox and August Daniel Reisert, citizens of the United States and residents of University City, St. Louis County, Missouri, and St. Louis, Missouri, respectively, have invented a new, original, and ornamental Design for a Combined Work Bench and Cabinet or Similar Article, of which the following is a specification, reference being had to the accompanying drawing, forming part hereof, in which

Fig. 1 is a top plan view;

Fig. 2 is a front elevational view; and

Fig. 3 is a side elevational view of a combined work bench and cabinet or similar article, showing our new design.

We claim:

The ornamental design for a combined work bench and cabinet or similar article, substantially as shown.

ALEXANDER P. FOX.
AUGUST DANIEL REISERT.
